UNITED STATES PATENT OFFICE.

WILLIAM C. STEVENS, OF AKRON, OHIO, ASSIGNOR TO THE FIRESTONE TIRE AND RUBBER COMPANY, OF AKRON, OHIO, A CORPORATION OF OHIO.

TIRE-VALVE STEM.

Application filed January 16, 1922. Serial No. 529,558.

The subject matter of this application is a stem for valves of pneumatic tires, it being the object of the invention to produce a better and cheaper valve stem than has 5 been manufactured heretofore. This invention relates to the valve stem as a new article of manufacture which may be manufactured in any suitable way, that described and claimed in Patent No. 1,506,457 granted 10 August 26, 1924, being a practicable and operative method.

In the drawing accompanying this application is shown one form of my invention, it being understood that changes and modifications 15 may be made in embodiments of my invention without departing therefrom, within the fair scope of the appended claim.

In the drawings:

Fig. 1 is a longitudinal section through a 20 valve stem embodying the features of my invention, the usual removable valve mechanism, or "insides" being omitted, as they may be of any well known or standard construction, and illustration thereof is not 25 deemed necessary.

Fig. 2 is a cross section on the line 2—2 of Fig. 1.

The valve stem is formed with the usual 30 barrel or stem 1, the outer surface of which is provided with the usual screw-threaded portions 2, and flattened areas 3. The base or foot of the valve stem 4 is separated from the main body or barrel of the stem by the usual groove 5, and is provided on its upper 35 face with the concentric grooves 6 which operate as a clamping means for the rubber inner tube, the stem being provided with the usual nut, not shown. The upper or outer end of the valve stem is formed with 40 the interiorly and exteriorly threaded nipple 7 for the reception of the valve cap and the threaded plug forming a part of the valve "insides."

Valve stems in use prior to my invention 45 have generally been made from a brass rod which is machined to its final shape, which operation has necessitated the use of extensive and expensive screw machines and the employment of skilled operators. One of 50 the points wherein my improved form of valve stem differs from those which have preceded it, is that the valve stem is made of cast metal, preferably aluminum which is die cast in molds under pressure. Much of

the surface of the stem can be formed in the 55 casting operation, the remaining work being done by stamping, machining or by some other mechanical operation. Aluminum will lend itself to this method of manufacture, and the resulting stem will be lighter and 60 cheaper than the usual brass stem now in use.

In the old form of valve stem, it is customary to form a ledge or seat some distance 65 within the passageway, which seat forms a resting place for the light metal foot at the base of the usual valve "insides." The spring of the valve mechanism is compressed between this foot and the screw-threaded plug fitting within the nipple of the valve stem. 70 In my improved valve stem the air passageway is indicated by the numeral 8. The lower part of the passageway contains a light metal tube 9, the upper edge of which, indicated by the numeral 10, forms the seat 75 for the foot of the valve mechanism. Any suitable means may be provided for keeping the tube in place in the valve stem, a suitable form of interlocking device being shown at 11. This interlock is formed by allowing 80 some of the metal to flow in around the lower edge of the tube and prevents the tube 9 from dropping into the inner tube of the tire. The tube 9 is prevented from falling in the other direction by the valve insides. 85 Any other suitable form of interlocking device may be employed if found suitable.

It will be seen that by the substitution of cast metal, such as aluminum, the manufacture of valve stems may be cheapened and 90 simplified. The machine work is greatly reduced over the old methods and an improved article is produced.

I claim:

A valve stem for use in pneumatic tires, 95 comprising a cast metal body portion having a central longitudinal bore, the upper portion of which is conical and the lower portion cylindrical, a tube of uniform cross-section throughout its length mounted within the cylindrical portion of the said bore, and a shoulder integrally formed with the stem for retaining the tube in position, the said tube forming a ledge at a point midway of the bore to support the valve mechanism. 100 105

WILLIAM C. STEVENS.
